9 Claims. (Cl. 113—1)

This invention relates to a device for feeding paper inserts into insets in can covers.

An object of the invention is to provide a device of simple construction which will effectively feed paper inserts into can covers.

Another object of the invention is to provide a device which is capable of operating at a high rate of speed in an economical and efficient manner.

10 A further object of the invention is to provide a means of inserting advertising matter in the form of paper booklets, cards or metal discs into insets in can covers or into other articles or packages having insets in their outer surfaces.

15 In the drawings:

Fig. 1 is a side elevational view of the machine.
Fig. 2 is a top plan view of the machine.

Fig. 3 is a cross-sectional view taken on line 3—3 of Fig. 3.

20 Fig. 4 is a cross-sectional view taken on line 4—4 of Fig. 3.

Fig. 5 is a cross-sectional view taken on line 5—5 of Fig. 2.

25 Fig. 6 is a cross-sectional view taken on line 6—6 of Fig. 5.

Fig. 7 is a fragmental elevation of the rotary inserting means of the invention.

Fig. 8 is a top plan view of a can taken on line 8—8 of Fig. 7.

30 There are various machines known to the art which are capable of performing the functions of the machine of this invention. These devices, however, are generally of an elaborate nature, containing many moving parts which necessarily involves a high initial cost and a similar cost of operation. Moreover, these machines are capable of feeding approximately sixty inserts per minute into can covers.

Our invention is of simple construction and is capable of feeding approximately one-hundred and fifty inserts per minute into can covers or packages. The machine as here set forth performs two functions; first, a reciprocating arm engages and moves an insert from a stack, and 45 deposits said insert upon an inset in a can cover and, secondly, a rotary inserting device then presses the insert into the inset.

The embodiment of our invention consists of a can conveyor in the form of a continuous chain 12 having equally spaced lugs 13 which form seats for the cans 14. The chain is driven over the conveyor structure 15 and a supporting table 16 by means of a gear 17 driven by a shaft 18. This shaft is driven by a sprocket 19 and chain 20 from reduction gearing 21. A motor 22 em-

ploying commercial electric current drives the reduction gearing through shaft 23 and flexible coupling 24.

An intermittent clutch 25 is driven from the reduction gearing by means of chain 26 and sprockets 27 and 28. The clutch is positioned on a shaft 29 held in bearings 30 which are mounted on standards 31. A driving clutch disc 32 carrying a lug 33 is made integral with the sprocket 28; both members running free on shaft 29. A driven clutch disc 34 fastened to the shaft 29 has a pin 35 outwardly urged by spring 350 and controlled by a lever 36 (Fig. 4). The pin has an inset 360 at its outer extremity to provide a clearance for the lug 33 when the pin is depressed by lever 36. When the lever is withdrawn, the pin urged outwardly by the spring, contacts the lug on the driving disc. The lever is bolted to a rod 37, supported by and freely movable in a guide 38 which is positioned on the standard 31. The lower end of the rod is bolted to an arm 39 which carries a plate 40 normally held in the path of the moving cans seated on the conveyor by a contraction spring 41 (Fig. 2).

Each can passing along the conveyor contacts the plate and moves the arm, thus imparting a rotary movement to the lever which releases the pin 35 and allows it to engage the lug 33 upon the driven disc 32. Rotary movement is thus imparted to the shaft 29 and the cam 42 which is fastened to its extremity. After the momentary contact with a can upon the conveyor, the arm is returned to its normal position by action of the spring 41. This action also places the lever in a position to receive and depress the pin 35 thus disengaging it from the lug on the driving disc. The pin has also an offset 340 in its outer surface to engage an inset 330 in the upper surface of the lever, to preclude movement of the disc when it is not being driven by the disc 32. Thus the clutch is synchronized with the moving cans so that the driven clutch disc carrying the pin and driving the cam revolves once for each can, while the driving clutch disc makes one revolution to actuate the clutch and one free revolution for each space between the cans.

A link 43 is fastened in a slot 44 in the cam by means of an adjustable lug 45. The link pivotally engages an inclined finger 46 riding in an inclined groove 47 upon the inclined table 48. The finger is controlled by the cam 42 and reciprocated in the groove with each actuation of the cam. A demountable knife 49 bolted to the top of the finger has an inset 50 slightly less than the thickness of one of the inserts. The recipro-

cating finger carries the knife in a slot 51 under the insert stacking base 52. The knife engages one of the inserts 53 from the stack and carries it through aperture 54 and deposits it upon the inset 55 in a can cover. A downwardly urged stop 56 allows but one insert to pass through the aperture 54, with each outward stroke of the finger. Preferably our stacking device consists of two vertically inclined bars positioned on the 10 stacking base 52 (Fig. 3) and against which the inserts 53 rest. When the insert stack is nearly exhausted it is only necessary to place additional inserts upon the stack to replenish it. The insert stack can, therefore, be replenished from time to time without necessitating the stopping of the entire mechanism thus providing a continuous feed which is highly desirous in this type of machine.

The inclined position of the table 48 and the 20 parts thereon allow an insert, engaged by the knife 49, to move downwardly in an inclined position so that the lower edge of the insert is brought close to its position in the inset of the cover of a moving can before the knife is withdrawn.

25 A rotary inserting means consisting of a shaft 56, a hub 57 positioned on the shaft having projecting arms 58 which carry circular cups 59 in which are seated rubber cylinders 60 having an inset 61 in their outer faces, is positioned on 30 standards 62. This inserting means is driven by a sprocket 63 and a chain 64 connected to shaft 18 of the conveyor mechanism. The rotary movement of this inserting means is so synchronized with the can conveying means that each 35 rubber cylinder contacts an insert upon a can cover. The rotary speed is somewhat faster than the can movement so as to allow the rubber cylinder to move the insert directly over the inset and then press the insert into the can cover.

40 What we claim is:

1. A machine for feeding paper inserts into insets in the covers of cans that are being moved by a conveyor, comprising the conveyor having 45 equally spaced lugs between which the cans are seated, a means for actuating the conveyor, a cam synchronized with the conveyor, an intermittent clutch means actuated by the movement of each can, the cam being controlled by the clutch means, a means for stacking the inserts, 50 a reciprocating knife actuated by the cam, the knife being adapted to engage and move the inserts from the bottom of the stack and deposit them upon the insets in the can covers, a rotary inserting means synchronized with the conveyor 55 and comprising a circular hub, a plurality of arms positioned on the hub, an insert engaging means positioned on the extremity of the arms and adapted to align the inserts with the insets and then press the inserts into the insets.

60 2. A machine for feeding paper inserts into insets in the covers of cans that are being moved by a conveyor, comprising the conveyor having 65 equally spaced seats for receiving the cans, a means for actuating the conveyor, a cam synchronized with the conveyor, an intermittent clutch means actuated by the movement of each can, the cam being controlled by the clutch means, a means for stacking the inserts, a reciprocating knife actuated by the cam, the knife 70 being adapted to engage and move the inserts from the stack to the insets in the can covers, a rotary inserting means synchronized with the conveyor and comprising a circular hub, a plurality of arms positioned on the hub, an insert 75 engaging means positioned on the extremities of

the arms and adapted to press the inserts into the insets.

3. A machine for feeding paper inserts into insets in the covers of cans that are being moved by a conveyor, comprising the conveyor having 5 equally spaced lugs between which the cans are seated, a means for actuating the conveyor, a cam synchronized with the conveyor, an intermittent clutch means actuated by the movement of each can, the cam being controlled by the 10 clutch means, a means for stacking the inserts, a reciprocating knife actuated by the cam, the knife being adapted to engage and move the inserts from the stack to the insets in the can covers, and a means synchronized with the conveyor 15 for pressing the inserts into the insets.

4. A continuous feed machine for feeding paper inserts into insets in the covers of cans that are being moved by a conveyor comprising the conveyor having 20 the cans, a means for actuating the conveyor, a cam synchronized with the conveyor, an intermittent clutch means actuated by the movement of each can, the cam being controlled by the clutch means, an inclined means for stacking the 25 inserts, a reciprocating knife actuated by the cam and adapted to engage and move the inserts from the bottom of the inclined stack to the insets in the cans, and a means synchronized with the conveyor for pressing the inserts into 30 the insets.

5. A machine for feeding paper inserts into insets in the covers of cans that are being moved by a conveyor comprising the conveyor having 35 equally spaced lugs between which the cans are seated, a means for actuating the conveyor, a cam synchronized with the conveyor, an intermittent clutch means actuated by the movement of each can, the cam being controlled by the clutch means, an inclined means for stacking 40 the inserts, a knife actuated by the cam to reciprocate in a plane at right angles to the inclined stacking means and also moving in the vertical plane of the movement of the cans, the knife being adapted to engage and move the inserts 45 from the stack to the insets in the cans, and a means synchronized with the conveyor for pressing the inserts into the insets.

6. A machine for feeding paper inserts into insets in the covers of cans that are being moved 50 by a conveyor comprising the conveyor having equally spaced seats for receiving the cans, a means for actuating the conveyor, a means for stacking the inserts, reciprocating means adapted to move the inserts from the stacking means to 55 the insets, a shaft, a cam fastened on the shaft, an intermittent clutch means comprising a driving clutch disk freely mounted on the shaft, means associated with the driving clutch disk and the means for actuating the conveyor for rotating 60 said clutch disk, a lug on the driving clutch disk, a driven clutch disk fastened to the shaft, an outwardly urged pin in the driven clutch disk, a lever adapted in normal position to engage the pin, and hold it outside the path of the lug and 65 in alternative position to release the pin into the path of the lug to cause engagement of the driving and the driven clutch discs, means actuated by the movement of each can to move the lever out of and back to normal position, and a 70 cam actuated by the driven clutch disc to control the movement of the reciprocating means.

7. A machine for feeding paper inserts into insets in the covers of cans that are being moved by a conveyor comprising the conveyor having 75

equally spaced seats for receiving the cans, a means for actuating the conveyor, a means for stacking the inserts, reciprocating means adapted to move the inserts from the stacking means to the insets, an intermittent clutch means actuated by the movement of each can and a cam synchronized with the conveyor and adapted to be actuated by the intermittent clutch means to control the movement of the reciprocating means.

8. A machine for feeding paper inserts into insets in the covers of cans that are being moved by a conveyor comprising the conveyor having equally spaced seats for receiving the cans, a means for actuating the conveyor, a means for stacking the inserts, reciprocating means adapted to move the inserts from the stacking means to the insets, an intermittent clutch means actuated by the movement of each can, a cam synchro-

nized with the conveyor and adapted to be actuated by the intermittent clutch means to control the movement of the reciprocating means, and means for pressing the inserts into the insets.

9. A continuous feed machine for feeding paper inserts into insets in the covers of cans that are being moved by a conveyor comprising the conveyor having equally spaced seats for receiving the cans, a means for actuating the conveyor, an inclined means for stacking the inserts, reciprocating means adapted to move the inserts from the stacking means to the insets, an intermittent clutch means actuated by the movement of each can and a cam synchronized with the conveyor and adapted to be actuated by the intermittent clutch means to control the movement of the reciprocating means.
